UNITED STATES PATENT OFFICE.

ETIENNE BUSCARLET, OF PARIS, FRANCE.

DESIGN FOR A GLOVE.

SPECIFICATION forming part of Design No. 26,818, dated March 30, 1897.

Application filed February 2, 1897. Serial No. 621,698. Term of patent 3½ years. Patented in France August 19, 1896, No. 17,932, and in England October 3, 1896, No. 285,425.

To all whom it may concern:

Be it known that I, ETIENNE BUSCARLET, a citizen of the Republic of France, residing at Paris, France, have invented a new and original Design for Gloves, (for which I obtained a French Patent, No. 17,932, dated August 19, 1896, and English Patent, No. 285,425, dated October 3, 1896, Cl. 10;) and I do hereby declare the following to be a full, clear, and exact description of the invention, such as will enable others skilled in the art to which it appertains to make and use the same, reference being had to the accompanying drawing, and to letters of reference marked thereon, which forms a part of this specification.

The leading feature of my design consists of a glove having the embroidery or raised ornamentation on the back of the glove disposed in divergent strips of unequal lengths and with a wristband or gauntlet parted from the main body of the glove by a V-shape raised ornamentation, and said wristband or gauntlet having an ornamental rear-edge-surrounding border.

In the accompanying drawing is illustrated in plan the back of a glove embodying the particular ornamental configurations and char-

acteristic ornamental features of design of a glove of my invention.

Referring to the drawing, A is the glove. 30
a is the wristband or gauntlet of the same, parted or separated by a V-shaped raised or embroidered ornamentation a' and with a rear-edge-surrounding ornamental or corded border a³.

35 The main portion of the back of the glove A, between the wristband or gauntlet portion a of the same and the fingers a⁴, has displayed three raised corded strips or embroidered ornamentations a² of unequal lengths, with the 40 spear-like embroidered or corded ornaments a⁶, disposed beyond the strips or ornamentations a², as illustrated.

Having thus described my invention, what I claim as new, and desire to secure by Letters 45 Patent, is—

The design for a glove, as illustrated and described.

In testimony whereof I affix my signature in presence of two witnesses.

ETIENNE BUSCARLET.
